UNITED STATES PATENT OFFICE.

BENJAMIN LIPPER, OF PHILADELPHIA, PENNSYLVANIA, ASSIGNOR TO HIMSELF, AUGUSTUS A. LAZARUS, AND ISAAC A. SCHWARZ, ALL OF SAME PLACE.

DESIGN FOR TRIMMING.

SPECIFICATION forming part of Design No. 18,253, dated April 10, 1888.

Application filed December 5, 1887. Serial No. 257,000. Term of patent 3½ years.

To all whom it may concern:

Be it known that I, BENJAMIN LIPPER, a citizen of the United States, and a resident of Philadelphia, Pennsylvania, have invented a new and original Design for Trimming, of which the following is a specification.

My design for a trimming is fully shown in the accompanying drawings, in which—

Figures 1 and 2 represent two styles of trimming, each embodying the design, Fig. 3 being a perspective view, on a larger scale, of the central web of the trimming, which constitutes a special and distinctive feature of the design.

The distinctive features of the complete design are the central web, *a*, outer bands, *b*, and cords *d*, extending in the curved courses shown from the central web to the outer bands, minor features of ornamentation being the loops *f*, which project from the opposite edges of the central web between the cords, and other loops, *g*, which project from the outer edges of the bordering bands *b*. The central web, *a*, comprises a series of bands, *m* and *n*, the bands *n* being flat, but the bands *m* having at intervals bunches of loops *h*, which project above the surface of the band, and thus form parallel rows of raised-loop bunches extending from end to end of the trimming.

The trimming shown in Fig. 1 has two bands *m* and one band *n* in the central web, while the web *a* (shown in Figs. 2 and 3) comprises three bands *m* and two bands *n*.

I claim—

1. The within-described design for a trimming, said design consisting of a central web having rows of loop bunches projecting above the face of the web, outer or bordering bands, and cords extending from the central web to the outer bands, all substantially as described and shown.

2. In a design for a trimming, the herein shown and described design for the central band, said design consisting of the parallel bands *m* and *n*, the latter being flat, and the bands *m* having at intervals bunches of loops raised above the surface of the band, all substantially as described and shown.

In testimony whereof I have signed my name to this specification in the presence of two subscribing witnesses.

BENJAMIN LIPPER.
